(57) **CLAIM**

The ornamental design for a taco plate, as shown and described.

DESCRIPTION

FIG. 1 is an isometric view of a taco plate, as shown and described;

FIG. 2 is a front view with a rear view being the mirror image thereof;

FIG. 3 is a right side view with a left side view being the mirror image thereof;

FIG. 4 is a top view thereof; and,

FIG. 5 is a bottom view thereof.

The broken lines are for illustrative purposes only and form no part of the claimed design.
